COMBINED VACUUM PRINTING FRAME, PHOTO-COPIER, LIGHT TABLE AND RULER

Edward A. Siraganian and Celia S. Siraganian, Los Angeles, Calif. (both of 1040 S. Bradshaw Ave., Monterey Park, Calif.)

Filed Oct. 1, 1963, Ser. No. 76,814

Term of patent 14 years

(D61—1)

Fig. 1

Fig. 2

Fig. 3

Fig. 4

FIGURE 1 is a front perspective view of a combined vacuum printing frame, photocopier, light table and ruler, showing our new design, with the glass cover and side leaf in open condition;

FIGURE 2 is a rear perspective view thereof with the cover and leaf in closed condition and the ruler removed;

FIGURE 3 is a perspective view thereof with the light box removed from its drawer to its light table position, and the overhead light removed; and

FIGURE 4 is an enlarged rear perspective view thereof with the ruler in place.

The essential features of our design are shown in full lines.

We claim:

The ornamental design for a combined vacuum printing frame, photocopier, light table and ruler, substantially as shown and described.
